UNITED STATES PATENT OFFICE.

MELVIN OVESTRUD, OF STILLWATER, MINNESOTA, ASSIGNOR TO TWIN CITY FORGE & FOUNDRY COMPANY, OF STILLWATER, MINNESOTA, A CORPORATION OF MINNESOTA.

MECHANISM FOR CONVEYING AND WATER-COOLING TIE-PLATES.

Application filed April 29, 1925. Serial No. 26,673.

My invention relates to improvements in mechanism for conveying tie-plates and cooling them in transit from a machine for forming the same to point of disposition thereof in a car or storage bin.

One form of tie-plate accommodated by the present improvement includes a platform having a flange traversing the same, said flange being heated in the forming process and bent to provide a jaw member for engaging the upper surface of the base of a rail seated on said platform. In one method of forming this tie-plate, the final steps comprise the heating of the flange and the bending thereof. Rapid production of these relatively heavy and bulky articles necessitates their prompt removal from the place of construction as by the disposition thereof in cars for shipping or bins for the storing thereof.

Being very hot during the bending of the flanges thereof, the tie-plates must be cooled to permit of the same immediately to be inspected, bundled and placed in cars or bins not proof against fire, and care must be taken that the metal be not hardened to too great an extent in the cooling of the tie-plates, since an over hardened tie-plate cannot be relied upon to function as intended.

An object of the present invention is to provide an improved means for conveying heated tie-plates and substantially cooling them in transit without hardening the same in detrimental degree.

With the foregoing and other objects in view, which will appear in the following description, the invention resides in the novel combination and arrangement of parts and in the details of construction hereininafter described and claimed.

In the drawings, Fig. 1 is a plan view of a mechanism embodying my invention; Fig. 2 is a vertical sectional view taken on a reduced scale as compared with that of Fig. 1 and as on the line 2-2 of said Fig. 1; Fig. 3 is a detail sectional view taken on the line 3-3 of Fig. 1 and Fig. 4 is a perspective view illustrating a tie-plate of the type that the present mechanism is particularly designed to accommodate.

Referring to the drawings, it will be seen that the illustrated embodiment of my invention includes an inclined trough A in the form of an I beam, the web 10 of the I beam

forming the bottom of the trough and the flanges 11 forming the sides thereof. Two standards B, C support the trough A, the upper end of each standard being socketed in a boss 12 on a yoke 13, the branches 13^a of which are pivoted to the trough flanges 11. The taller standard B comprises telescoping members 14, 15, the upper member 15 being adjustable vertically of the base member 14 to vary the inclination of the trough A. Projecting from each end of the trough A are a pair of brackets 16, one bracket of each pair being secured to one of the flanges 11 and the other bracket of each pair to the other flange 11. An idler shaft 17, journaled in the lower brackets 16, carries a sprocket 18. A drive shaft 19, journaled in the upper brackets 16 carries a second sprocket 20 and a power pulley 21. Running over said sprockets 18, 20 is an endless chain 22 fitted with outwardly projecting link extensions 23. Said sprockets 18, 20 are located with respect to the trough A so that the upper reach of the chain 22 travels on the web 10 of the trough and near one of the flanges 11, the lower reach of said chain hanging from the sprockets 18, 20 beneath the trough A. Carried over the upper end of the trough A, in brackets 24 rising from one of the flanges 11 thereof, is a sprinkler nozzle 25, the same being connected with a water feed pipe 26 and adapted to spray water downwardly into the trough A in substantial volume.

A formed tie-plate D (Fig. 4) passed immediately from the press for bending the heated flange thereof is placed in the trough A, bent flange 26 downward, with one margin of the platform 27 riding on the edge of the flange 11 adjacent the chain 22 and the other margin thereof riding on a wearing rail 28 placed in the angle between the web 10 and the other flange 11. Thus disposed, the tie-plates D rest in inclined positions transversely of the trough, the depressed ends being guided by that portion of the flange 11 above the wearing rail 28, and the hot bent flanges 26 of the tie-plates hanging in the flow of water down the trough A. In practice the device is arranged between a bending press and a car or bin for receiving formed tie-plates, the lower end of the trough A being adjacent to the press and the upper end thereof over-

hanging a car or bin for receiving the formed tie-plates. Power is applied to the pulley 21 to rotate the same in a counterclockwise direction as seen in Fig. 2. Thus turned, 5 the rotation of said pulley 21 results in the upward travel of the upper reach of the chain 22 in the trough A. Tie-plates D stationed on the lower end of the trough A are carried upwardly thereon by the link extensions 23 on the chain 22.

The placing of tie-plates on the trough A and between the link extensions 23 as said tie-plates issue from the forming press, results in a continuously advancing train of 15 such plates upwardly of the trough, new plates being added to the train at the bottom of the trough to replace those discharged therefrom at the upper end thereof. Water sprinkled from the nozzle 25 onto the tie-plates at the upper end of the trough A is caught by and flows downward through said trough into a drain pipe 29 at the lower end thereof. Contacting with the plates in its 20 downward flow in the trough A, the water is heated thereby, the temperature of the water increasing as it approaches the lower end of the trough. Under these circumstances it will be seen that the hottest plate is subjected to the hottest water and, 25 conversely, that the cooler the plate, the cooler the water applied thereto. With the speed of the chain 22 properly timed with regard to the inclination of the trough A, the tie-plates issue, from the upper end of the 30 trough, without being detrimentally hardened, and cool enough to permit of the handling thereof or the safe disposition of the same in a car or bin not proof against fire.

Changes in the specific form of my invention, 40 as herein disclosed, may be made within the scope of what is claimed without departing from the spirit of my invention.

Having described my invention, what I claim as new and desire to protect by Letters 45 Patent is:

1. In a device of the class described, an inclined trough constituting spaced rails for slidably supporting objects along said trough, a conveyer adapted to slide objects 50 along side rails from bottom to top of the trough, said conveyer being arranged to one side of said trough to provide an unobstructed way in the trough in which the most highly heated portions of said objects may be disposed, and means for introducing water into 55 said trough at the upper end thereof.

2. In a device of the class described, an inclined trough, a conveyer occupying a limited part of the width of said trough for 60 conducting objects heated only at portions thereof from the bottom of the trough to the top thereof with the portions of said objects most highly heated disposed in that portion of the trough unobstructed by said conveyer and means for introducing water 65

at the upper end of the trough into said portion thereof.

3. In a device of the class described, an inclined trough, means for introducing water thereto at the upper end thereof, a conveyer 70 occupying a relatively small lateral portion of said trough for conducting objects heated only at portions thereof from the bottom of the trough to the top thereof with the portions of said objects most highly heated 75 disposed in that portion of the trough unobstructed by said conveyer.

4. In a device for conveying and cooling objects heated at portions thereof only, an inclined trough including a bottom and 80 sides, a conveyer relatively narrow as compared to the width of said bottom disposed within said trough near one of the sides thereof to provide a free space on the other side of said conveyer, said objects being 85 arranged upon said conveyer with the heated portions thereof in the free space in said trough, and means for introducing water at the upper end of the trough in said free space.

5. In a device for conveying and cooling objects heated at portions thereof only, an inclined trough including a bottom and 90 sides, a conveyer relatively narrow as compared to the width of said bottom disposed within said trough near one of the sides thereof, a sprinkler nozzle disposed at the upper end of said trough at the side thereof opposite said conveyer, said objects being 95 moved along said trough with the heated portions thereof in line with said sprinkler nozzle and opposite to said conveyer.

6. In a device for conveying and cooling tie plates heated along a portion thereof, an inclined trough including a bottom and 105 sides, a conveyer relatively narrow as compared with said bottom and disposed near one of the sides thereof to provide a free space along the other side of said trough, said trough being of a width narrower than the tie plates, said tie plates being arranged 110 to ride upon the edge of said trough side near said conveyer with the heated portions thereof extending into the free space in said trough, said trough and conveyer being so proportioned as to cause the conveyer to engage said tie plates substantially in alignment with their centers of gravity, and means for discharging water into the free space within said trough at the upper portion thereof.

7. In a device for conveying and cooling tie plates heated along a portion thereof, an inclined trough including a bottom and 125 sides, a conveyer relatively narrow as compared with said bottom and disposed near one of the sides thereof to provide a free space along the other side of said trough, said trough being of a width narrower than the tie plates, said tie plates being arranged 130

to ride upon the edge of said trough side near said conveyer with the heated portions thereof extending into the free space in said trough, said trough and conveyer being so proportioned as to cause the conveyer to engage said tie plates substantially in alignment with their centers of gravity, a wearing rail disposed within said trough at the bottom thereof adjacent said trough side

opposite said conveyer for supporting said tie plates and holding the same out of contact with said trough, and means for discharging water into the free space within said trough at the upper portion thereof.

In testimony whereof, I have signed my name to this specification.

MELVIN OVESTRUD.
